(57) **CLAIM**

What is claimed is the ornamental design for a surgical suction filter, as shown and described.

DESCRIPTION

FIG. 1 is an exploded perspective view of a design for a surgical suction filter.

FIG. 2 is a perspective view of the design shown in FIG. 1. FIG. 3 is a side view of the design shown in FIG. 1.

FIG. 4 is a perspective view of a filter body of the design shown in FIG. 1, shown separately for ease of illustration. FIG. 5 is a side view of the filter body shown in FIG. 4. FIG. 6 is an opposite side view of the filter body shown in FIG. 5.

FIG. 7 is a top end view of the filter body shown in FIG. 4. FIG. 8 is a bottom end view of the filter body shown in FIG. 4.

FIG. 9 is a perspective view of a filter element of the design shown in FIG. 1, shown separately for ease of illustration. FIG. 10 is a side view of the filter element shown in FIG. 9. FIG. 11 is a top view of the filter element shown in FIG. 9. FIG. 12 is a bottom view of the filter element shown in FIG. 9.

FIG. 13 is a perspective view of a cap of the design shown in FIG. 1, shown separately for ease of illustration.

FIG. 14 is a side view of the cap shown in FIG. 13.

FIG. 15 is a bottom view of the cap shown in FIG. 13.

FIG. 16 is a top view of the cap shown in FIG. 13.

FIG. 17 is a perspective view of a ring of the design shown in FIG. 1, shown separately for ease of illustration.

FIG. 18 is a top view of the ring shown in FIG. 17.

FIG. 19 is a side view of the ring shown in FIG. 17.

FIG. 20 is an opposite side view of the ring shown in FIG. 17.

FIG. 21 is an end view of the ring shown in FIG. 17.

FIG. 22 is an opposite end view of the ring shown in FIG. 17.

FIG. 23 is a perspective view of a clip of the design shown in FIG. 1, shown separately for use of illustration.

FIG. 24 is a top view of the clip shown in FIG. 23.

FIG. 25 is a side view of the clip shown in FIG. 23.

FIG. 26 is bottom view of the clip shown in FIG. 23.

FIG. 27 is an opposite side view of the clip shown in FIG. 23.

FIG. 28 is an end view of the clip shown in FIG. 23; and, FIG. 29 is an opposite end view of the clip shown in FIG. 23.

The broken lines show portions of the surgical suction filter that form no part of the claimed design.
